Primary Examiner — Elizabeth J Oswecki(74) *Attorney, Agent, or Firm* — Lightbulb IP, LLC(57) **CLAIM**

The ornamental design for pumpkin arm, as shown and described.

DESCRIPTION

FIG. 1 is a front view of a first embodiment of a right side pumpkin arm showing my new design;

FIG. 2 is a back view thereof;

FIG. 3 is a side view thereof;

FIG. 4 is an opposite side view of FIG. 3 thereof;

FIG. 5 is a bottom view thereof;

FIG. 6 is a top view thereof;

FIG. 7 is a front view of a second embodiment of a left side pumpkin arm showing my new design;

FIG. 8 is a back view thereof;

FIG. 9 is a side view thereof;

FIG. 10 is an opposite side view of FIG. 9 thereof;

FIG. 11 is a bottom view thereof; and,

FIG. 12 is a top view thereof.

The portions shown in broken lines in the drawings illustrate an environment and are not part of the claimed design.
